UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

MULTIPLE-NEEDLE WEFT DETECTOR FOR LOOMS.

Application filed June 9, 1926. Serial No. 114,813.

This invention relates to improvements in multiple needle weft detectors for looms and it is the principal object of the invention to simplify and cheapen the construction of this 5 type of detector by making certain portions of pressed metal and by dispensing with the necessity for close fitting such as has prevailed heretofore in mechanisms of this type.

In weft detectors of the type specified it 10 has been the usual custom to provide a detecting element having two parallel arms one of which is longer than the other and engages the bobbin while the shorter arm serves as a controller for an actuating lever. These 15 detecting elements have been slidably mounted in a frame and it has been a matter of practical difficulty to have the arms the same distance apart in all of the elements, a condition which is necessary in order to permit 20 the free movement necessary to render the detector sensitive and delicate in its operation. It is a further object of my invention to avoid the close fitting by using a detector having a single arm provided at its forward end with a short hook which cooperates 25 with supporting means, the needles being guided in a frame preferably of pressed metal.

In Patent No. 1,583,135 issued to Flanigan 30 and Ashton there are shown a plurality of individual weights, one for each detector and it is a further object of my invention to use this construction by pivotally connecting each of the needle detectors to its corresponding weight, thus simplifying the construction and insuring that each detector will be at all times operatively connected to its weight.

The actuator previously mentioned has 40 heretofore cooperated with the shorter arm of the indicating needle but this practice has resulted in occasional bending of the controller ends of the needles so that the same do not move freely in their guides and it is a 45 still further object of my invention to overcome this objection by forming each weight with a controller portion which will act to interrupt the downward movement of the actuator lever. By this construction it is 50 possible to make use of a controller the width of which is substantially equal to the distance between adjacent detector needles and said portion can be made much stronger

than the needle and will therefore be more satisfactory and subject to less deformation. 55

With these and other objects in view which will appear as the description proceeds, my invention resides in the combination and arrangement of parts hereinafter described and set forth in the claims. 60

In the accompanying drawings wherein I have shown a convenient embodiment of my invention,

Fig. 1 is a side elevation of my improved detector, portions thereof, together with the 65 cooperating shuttle and bobbin, being indicated in section,

Fig. 2 is a top plan view of the detector taken in the direction of arrow 2, Fig. 1, the guide for the actuator lever being shown 70 in section,

Fig. 3 is a rear elevation of the detector taken in the direction of arrow 3, Fig. 1,

Fig. 4 is a detail side elevation of one of the weights and the adjacent portion of the 75 corresponding needle detector, parts being in section to indicate the connection between the two parts, and

Fig. 5 is an enlarged horizontal section on line 5—5 of Fig. 4, looking in the direction 80 of the arrows.

Referring particularly to the drawings it will be seen that I have provided a stand 10 having bolted thereto a support 11 on which is mounted a carrier 12. Said carrier 85 is preferably formed of a piece of sheet metal and has a rearwardly extending arm 13 upturned as at 14 to guide the rearwardly extending portions of the needle detector's 15, the latter passing through perforations 16. 90 The carrier is also formed with a second forwardly extending arm 17 hooked as at 18 to receive the forward end of the tension spring 19. The latter extends through an upright offset connecting portion 20 of the carrier between the arms 13 and 17 and also extends 95 through the support 11 and is held to the rear end thereof by a pin 21. By the construction last described the carrier is held yieldingly to the support so that it may move 100 forwardly if engaged by a misplaced bobbin or other obstruction.

The carrier is provided with a pair of spaced upstanding wings 22 between the upper ends of which extends a pin 23. 105 Weights 24 are loosely pivoted on pin 23 and

have their lower ends formed with a rearwardly extending finger 25 which is forked as indicated in Figs. 4 and 5. A small rivet 26 extends between the ears 27 and serves normally to support the forward hooked end 28 of the detector needles 15. The parts are proportioned as indicated in Figs. 4 and 5, disconnection of the parts being prevented under normal conditions.

10 Each weight 24 is provided with a depending lug 29 to engage a stop 30 riveted or otherwise secured to the arm 17 and having a leather pad 31 to lessen wearing of the lugs 29 and limit movement of said weights and 15 detectors.

Each weight is provided with a recess 32 which is normally occupied by a rod 33 extending between opposite depending arms 34 of withdrawing element 35 having a forwardly extending arm 36. Said withdrawing element is pivoted on the pin 23 and lies outside the wings 22, the connecting portions between the arms 34 serving to reinforce the wings, resulting in proper holding 20 of the weights. At the time of transfer the arm 36 is moved forwardly and upwardly and the rod 33 withdraws the weights and also the needle detectors from operative position.

30 As indicated in Figs. 1 and 2 there is provided an actuator 37 which is similar to the actuator set forth in Patent No. 1,030,748 and has a downward movement each detecting beat of the loom, being guided by a 35 slotted stand 38 indicated in Fig. 2. When the actuator lever is permitted to move downwardly without interruption no indication is given to the weft replenishing mechanism (not shown) but when descent 40 is prevented the lever acts to indicate weft exhaustion to effect a change in the loom.

45 Interruption of the normal descent of the actuator lever is accomplished by means of lugs 39 formed on the weights 24. These lugs may be formed as indicated in Figs. 1 and 4 with a downwardly and forwardly inclined upper face to cooperate with the similarly formed lower edge of the actuator lever 37.

50 Under normal conditions the parts will be as indicated in Fig. 1 with the lugs 39 lying under the actuator lever 37. When a sufficient supply of weft W is moved forwardly by the lay L the detectors 15 will move 55 through a slot 40 in the shuttle S and said detectors will be moved forwardly, carrying the lugs 39 to the dotted line position indicated in Fig. 1 and out of the path of the actuator. The latter may therefore descend without interruption. When insufficient yarn for continued weaving is present, however, one or another of the needle detectors 15 will enter a hole 41 in the bobbin B and the corresponding weight will therefore remain in normal position with its lug

39 under the actuator lever 37. Descent of the latter is therefore prevented and an indication to the weft replenishing mechanism results. The bobbin B may be made as set forth in Patent No. 1,220,685 to Ryon or No. 1,337,706 to Jenckes.

From the foregoing it will be seen that I have provided a very simple multiple needle weft detector wherein there is positive connection between the needle detectors 15 and the weights 24, the latter serving to return the detectors to normal position and the detectors being formed as a straight wire with a hook at one end. It will also be seen that the downward pressure of the actuator lever 37 is taken by one or another of the lugs 39 and as indicated in Fig. 2 these lugs are larger than the needle detectors and are therefore subject to less bending. It will further be seen that the carrier for the needles and weights is made of sheet pressed metal so as to be of light construction and that the guides for the detectors are holes punched through a portion of the carrier. Furthermore, the detectors can be removed from their weights by bending the stop 30 forwardly to permit the rear end of the detector to be removed from the corresponding opening 16, after which the detector can be raised and then slid off the stud 26 because of the open construction of the hook 28.

Having thus described my invention it will be apparent that changes and modifications may be made therein by those skilled in the art without departing from the spirit and scope of the invention, and I do not wish to be limited to the details herein disclosed but what I claim is:

1. A loom weft detector to cooperate with a bobbin provided with a plurality of holes which are uncovered at substantial exhaustion of weft, a plurality of individually movable detectors, and a weight for each detector, each weight being pivotally connected to its corresponding detector and moving therewith and acting by gravity to move the corresponding detector to normal position.

2. A loom weft detector to cooperate with a bobbin provided with a plurality of holes which are uncovered at substantial exhaustion of weft, a plurality of individually movable needle detectors, a plurality of individually movable weights, each detector having a hook formed on the forward end thereof, and means defining a positive pivotal connection between the hooked end of each detector and the corresponding weight, the weights acting by gravity to restore the detectors to normal position.

3. A loom weft detector to cooperate with a bobbin provided with a plurality of holes which are uncovered at substantial exhaustion of weft, a plurality of individually

movable needle detectors, a plurality of individually movable weights, each detector having a hook formed on the forward end thereof, and means defining a positive pivotal connection between the hooked end of each detector and the corresponding weight, the weights acting by gravity to restore the detectors to normal position, the hook being opened a sufficient amount to slip over the pivotal connection of the corresponding weight so that each weight may be disconnected from its corresponding detector.

4. A loom weft detector to cooperate with a bobbin provided with a plurality of holes which are uncovered at substantial exhaustion of weft, a support, a plurality of individually movable weights mounted for pivotal motion on the support, and a plurality of needle detectors one for each weight, the support being provided with guide openings to receive the rear ends of the detectors, said detectors being supported in part directly by the support and in part by the weights.

25 5. A loom weft detector to cooperate with a bobbin provided with a plurality of holes which are uncovered at substantial exhaustion of weft, a plurality of weights, a support for said weights on which the latter are movably mounted, and a plurality of needle detectors one for each weight, each detector being supported in part by the associated weight, said weights acting by gravity to move the detectors to normal position.

35 6. A loom weft detector to cooperate with a bobbin provided with a plurality of holes which are uncovered at substantial exhaustion

tion of weft, a support, a plurality of weights movably mounted on the support, a plurality of needle detectors one for each weight, means defining a positive connection between each weight and the associated detector, and means acting on the weights at the time of transfer to withdraw the detectors from the path of the incoming bobbin.

7. A loom weft detector to cooperate with a bobbin provided with a plurality of holes which are uncovered at substantial exhaustion of weft, a plurality of needle detectors, a sheet metal carrier therefor having a portion thereof bent vertically and perforated to receive and guide and support the detectors, said carrier having formed integrally therewith lateral upstanding wings, a pivot pin extending between the wings, and a plurality of weights movably mounted on the pin, one weight for each detector, the weights extending between and being restrained against lateral movement by the wings.

8. A weight for a multiple needle weft detector operating with a plurality of needle detectors and an actuator lever, said weight having provision for pivotal connection with a needle detector, and having also a projection to lie normally under the actuator.

9. A combined weight and detector element for a multiple needle weft detector operating with a plurality of needle detectors, said weight and detector element being pivotally connected to each other.

In testimony whereof I have hereunto affixed my signature.

ELBRIDGE R. HOLMES.
